US00D339155S

United States Patent [19]

Suzuki et al.

[11] Patent Number: Des. 339,155

[45] Date of Patent: ** Sep. 7, 1993

[54] DOCUMENT FEEDER FOR COPYING
MACHINE

D. 307,158 4/1990 Perry D18/38
D. 312,653 12/1990 Nakamura et al. ....
D. 318,485 1/1989 Hikawa et al. ....
4,664,509 5/1987 Christy et al. 355/75

[75] Inventors: Yuji Suzuki, Tokyo; Yoshihisa
Minakawa, Yokohama, both of Japan

Primary Examiner—Alan P. Douglas

Assistant Examiner—Caron D. Veynar

Attorney, Agent, or Firm—Oblon, Spivak, McClelland,
Maier & Neustadt

[73] Assignee: Ricoh Company, Ltd., Tokyo, Japan

[**] Term: 14 Years

[57] CLAIM

[21] Appl. No.: 620,284

The ornamental design for document feeder for copy-
ing machine, as shown and described.

[22] Filed: Nov. 30, 1990

DESCRIPTION

[30] Foreign Application Priority Data

Jun. 8, 1990 [JP] Japan 2-19391
[52] U.S. Cl. D18/49; D18/46
[58] Field of Search D18/36-40,
D18/46, 49; 271/3, 3.1, 8.1, 9; 355/200, 308,
309; 358/498

FIG. 1 is a top, front and right side perspective view of
a document feeder for copying machine showing our
new design;
FIG. 2 is a bottom, rear and left side perspective view
thereof;
FIG. 3 is a front elevational view thereof;
FIG. 4 is a rear elevational view thereof;
FIG. 5 is a right side view thereof;
FIG. 6 is a left side view thereof;
FIG. 7 is a top plan view thereof; and,
FIG. 8 is a bottom plan view thereof.
